Inventor:
Gottlieb Niebel.

UNITED STATES PATENT OFFICE

GOTTFRIED NIEBEL, OF NEW YORK, N. Y.

DESIGN FOR AN ELECTRIC BULB OR SIMILAR ARTICLE

Application filed January 3, 1930, Serial No. 34,007, and in Germany September 6, 1929. Term of patent 14 years.

To all whom it may concern:

Be it known that I, GOTTFRIED NIEBEL, a citizen of the United States, and resident of 419 West 115th Street, in New York, in the county of New York, and State of New York, have invented a certain new, original, and ornamental Design for an Electric Bulb or Similar Article, of which the following is a specification, reference being had to the accompanying drawing, forming part thereof.

The view is an elevation of an electric bulb or similar article showing one side of my new

design, the opposite side of the design being the same as that which is shown by this view. The electric bulb is substantially circular throughout.

I claim:

The ornamental design for an electric bulb or similar article substantially as shown and described.

Signed at New York in the county of New York and State of New York this thirtieth day of December A. D. 1929.

GOTTFRIED NIEBEL.
